UNITED STATES PATENT OFFICE

HERMAN A. NORTH, OF BOGOTA, NEW JERSEY

PROTECTIVE GARMENT

Application filed November 15, 1928. Serial No. 319,669.

This invention relates to protective garments and I use this title not in the sense that the garment is primarily designed to protect the wearer but to prevent the theft of money or other valuables carried by the

5 garment. My improved garment is designed to be worn by a messenger carrying money or valuables so that the money or valuables can be 10 distributed throughout the pockets or compartments on the inner face of the garment, and the garment securely locked on the body of the user.

A further object is to provide a protective 15 garment which is in the nature of an improvement on my Patent No. 1,520,962, granted December 30, 1924.

A further object is to provide a protective garment with an improved arrangement of 20 flaps that prevent any possibility of a thief forcing his hand into the interior of the garment and removing the contents of the pockets or compartments therein.

The primary use of this device is to prevent 25 holdups, making it necessary to kidnap the messenger in order to secure the valuables he carries, as it is practically impossible for thieves to secure the valuables or remove the garment from the wearer during the short 30 time which holdup men have in which to make a successful robbery. Furthermore, the garment prevents any collusion between the messenger and the thieves as it cannot be removed by the messenger or any of the 35 contents thereof removed by him.

With these and other objects in view, the invention consists in certain novel features of construction and combinations and arrangements of parts, which will be more fully 40 hereinafter described and pointed out in the claims.

In the accompanying drawings—

Figure 1 is a plan view looking at the inner 45 face of the garment, with the garment extended and some of the covering flaps thrown backwardly;

Figure 2 is a perspective view showing the garment in use on the messenger;

50 Figure 3 is an exaggerated view in section on the line 3—3 of Figure 1;

Figure 4 is an exaggerated view in section on the line 4—4 of Figure 2;

Figure 5 is an exaggerated view in section on the line 5—5 of Figure 1.

My improved garment 1 is made of any 55 suitable flexible material, and while I show the garment as having armholes 2 therein, so that it has somewhat the appearance of a vest, it is obviously within the scope of the invention to make the garment of any form de- 60

The material of the garment must in itself be such that it is difficult and practically impossible to cut or tear the material, and I may employ a material having this desirable 65 feature or I may employ some other material and protect the same by additional means or devices; for example, in the drawings I show the material as carrying metal buttons or rivets 3 which are secured in the material 70 and so closely associated as to make it quite impossible for any cutting of the garment by an ordinary tool or means.

At the front of the garment I employ metal 75 plates 4 and 5, one plate having staples 6 thereon and the other having openings 7 therein to receive the staples so that when the garment is placed around the body padlocks 8 may be projected through the staples to secure the garment on the user.

It is to be understood that the messenger will not have any keys for the padlocks so that he cannot remove the garment. The keys may be held at the bank and at the place of delivery or only at the latter place, if desired, the padlocks being opened before the messenger is sent to the bank and then snapped into closed position when the garment is on the messenger and he is about to return with the money in the garment.

As a means for permitting an adjustment 85 of the garment in accordance with the size of the wearer or of the bulging of the pockets of the garment, one of these plates 5 may be made in two sections hinged together, as indicated in Figure 1, so that this plate may be 90 folded and the openings 7 in the sections will register when the plate is folded.

9 represents a series of pockets, which may be in any number, arranged in any suitable 100

manner and of any shape or material desired. These pockets are distributed throughout the interior of the garment both for distribution of the weight and also to make the garment more comfortable for the wearer.

5 In order to prevent a thief from slipping his hand into the garment, either from above or below, I provide an improved arrangement of flaps which will now be described. A flap 10 is located at the lower edge of the garment and is folded inwardly and against the lower pockets 9 and is provided with any desired number of strips 11 which extend upwardly. The flap 10 and the strips 11 are preferably 10 provided with some means whereby they may be connected to the inner portion of the garment, and I have illustrated for this purpose snap fasteners, the flaps 10 and strips 11 having snap fastener members 12 which engage 15 snap fastener members 13 on the pockets 9 and on the inner face of the garment.

Covering strips or flaps 14 are secured to the top and front edges of the garment and are adapted to fold inwardly one upon the 20 other and are also provided with snap fastener members 12 or other suitable fastening means co-operating with snap fastener members 13 inside of the garment to connect with and hold them in place.

25 30 When the pockets are filled and the flaps and strips 10, 11 and 14 are folded inwardly they will extend over the pockets and will prevent any opening or removal of the contents of the pockets by the insertion of a hand 35 either at the top or bottom of the garment.

I do not of course limit myself to the precise shape and arrangement of covering flaps and strips but it is a preferred arrangement to have them so arranged that they extend over 40 the pockets or covering flaps on the pockets and assist in holding the pockets or the covering flaps in closed position in addition to preventing a thief from forcing his hand inside the garment and opening or removing 45 the contents from the pockets.

All of the features of my improved garment have the same end in view, that is, to prevent a thief from securing the contents of any of the pockets either by removing the 50 garment or by forcing his hand inside the garment.

Various changes and alterations might be made in the general form of the parts described without departing from my invention 55 and hence I do not limit myself to the precise details set forth but consider myself at liberty to make such changes and alterations as fairly fall within the spirit and scope of the appended claims.

60 I claim:

1. A protective garment having compartments or pockets on its inner face, a covering flap extending upwardly from the bottom of the garment and removably connected to the 65 inner face of the garment over certain of the

compartments or pockets, and strips on said flaps extending upwardly and removably connected to other of said compartments or pockets and to the garment.

2. A protective garment having compartments or pockets on its inner face, a covering flap extending upwardly from the bottom of the garment and removably connected to the inner face of the garment over certain of the compartments or pockets, strips on said flaps 70 extending upwardly and removably connected to other of said compartments or pockets and to the garment, and other covering flaps and strips located at the upper and front edges of the garment and adapted to be removably connected to the inner face of the garment and cover the pockets or compartments therein.

3. A protective garment adapted to fit and be secured around the body of the wearer and 85 having armholes therein, pockets on the inner face of the garment, and an upwardly extending flap located at the lower and inner portion of the garment and positioned over certain of the pockets whereby a hand cannot be 90 forced upwardly inside of the garment and have access to the pockets.
